UNITED STATES PATENT OFFICE.

WILLIAM TAYLOR, OF LEICESTER, ENGLAND.

DIVIDING-HEAD.

1,323,658.

Specification of Letters Patent.

Patented Dec. 2, 1919.

Application filed August 9, 1917. Serial No. 185,264.

To all whom it may concern:

Be it known that I, WILLIAM TAYLOR, a subject of the King of England, residing at Leicester, in the county of Leicester, England, have invented a certain new and useful Improved Dividing-Head, of which the following is a specification.

This invention relates to appliances for dividing circular or other objects, as in graduated, engraving, machining, and has for its object to provide improved means for chucking them and rotating them into and holding them in proper operative relation to the dividing, engraving or machining tools.

The invention embodies various improvements on the appliance for this purpose shown in the specification of prior British Letters Patent, granted to William Taylor and others, No. 6420 of 1894, wherein a work-holding plate or chuck, adapted to be rotated manually and clamped in successive operative positions to effect the dividing, was provided with means for determining or indicating such positions, and with means for inclining the axis of rotation of the work-holder into any position from vertical to horizontal.

The subject of my present invention in its preferred form is illustrated by the accompanying drawings, in which—

Figure 1 is a plan view of the dividing-head with the axis of the work-holder set vertically;

Fig. 2 is an end elevation showing in full lines the work-holder which is shown in plan in Fig. 1, and in dotted lines the work-holder inclined at an angle of 45° to the vertical;

Fig. 3 is a side elevation of the apparatus viewed in the direction of the arrow placed in Fig. 1;

Figs. 4 and 5 are respectively plan and front elevations of a catch-disk or index-plate for determining the angular positions to which the work-holder is rotatable about that axis which, in Fig. 1, is vertical, and a separate collar for adjustably securing the index-plate to the work-holder; and

Fig. 6 is a view of a detail B hereinafter particularly described.

Like reference-letters indicate like parts throughout the drawings.

Referring now to these drawings, a chuck or holder A for the work is adapted to rotate on a journal A¹ (Fig. 3), in a rigid

supporting member B, in which it may be 55 clamped by means of a screw B¹, which is threaded into the member B and adapted to close, radially on to the journal A¹, a part B² (cross-hatched in Fig. 1 not to indicate that the part is in section, but merely to enable its position and extent to be more clearly apprehended) of the journal bearing, which part is for the purpose sufficiently detached (as shown in the separate view Fig. 6 which illustrates the part B removed from Fig. 1) 60 65 from the member B to enable it to be thus closed.

A convenient way of securing this partial detachment is to core through the member B a slot S, Figs. 1 and 6, so as to leave the part 70 B² in the form of a semicircular and preferably flexible strap united with the supporting member B at one end and adapted to be sprung inward at the other end so as to press, like one-half of a band-brake, on the 75 journal A¹, and also force it radially toward the fixed half of the bearing. The part B² is preferably made flexible for the purpose of insuring that when it is forced inward 80 against the journal A¹ it shall not only force the journal against the fixed half of the bearing but also shall close in on all sides of the arc of the journal which is embraced by it, thereby preventing all side shake and insuring that the axis of the journal A¹ at all 85 times after the journal has been clamped shall in relation to the supporting member B and to the support of the pawl D (hereinafter described) have one invariable position only. In order further to secure accuracy of position of the work-holder axis when its journal A¹ is thus held by the strap B², I may cut away a segment of the surface of the bearing, for example at 2 opposite the point U where the strap puts its 95 maximum pressure on the journal, so that the journal is held at such point and at points V, W, on either side of said segmental clearance, such points thus constituting at least a three-point bearing. This arrangement, beside having the merit of simplicity, 100 renders the accuracy of dividing independent of wear or looseness of the journal.

The supporting member B is carried adjustably by a base F (which with the means 105 for retaining and adjusting the supporting member upon it hereinafter described are not of the present invention) so as to vary,

in the manner indicated by Fig. 2, the inclination of the axis of the work-holder A, and for this purpose there is provided integral with the member B a part-cylindrical piece B²⁰ whose axis x y (Fig. 1) preferably intersects the axis a³ a⁴ (Fig. 2) of the work-holder, and at right-angles.

The part-cylindrical piece B²⁰ has formed in and around its periphery a T slot B³, and sits and turns in a corresponding part-cylindrical surface F⁵ on the base F, being guided in its movement about the axis x y (Fig. 1) and prevented from moving along that axis by a tongue F⁶ which fits (see Fig. 1) in the open or "stem" part of the T slot B³. The cylindrical surface of the part B²⁰ is held against the surface F⁵ on the base by a bolt F⁷ with head F⁸ adapted to engage within the head or cross-portion 10 of the T slot B³, and caused to draw the part B²⁰ radially into engagement with the surface F⁵ by means which may comprise a thrust piece F⁹ (Fig. 2) and a screw F¹⁰, which is threaded into the part F and may 15 be operated by a removable key F¹¹.

In order to prevent the contiguous part-cylindrical surfaces of the parts B²⁰ and F from becoming sufficiently separated to admit chips or dirt when the screw F¹⁰ is slackened, a second thrust-piece F¹² is provided, and an adjusting-screw F¹³ therefor. This second thrust-piece, while it is adapted to prevent the said surfaces from being so separated, is so adjusted as to leave them 20 free to slide relatively, in a circular arc when the screw F¹⁰ is slackened.

It will be seen from Fig. 2 that there are two flats F²¹ F²² at an angle on the stem of the bolt F⁷; it is upon the flat F²¹ that the thrust-piece F⁹ bears and upon the flat F²² that the second thrust-piece F¹² bears, so that the thrust-pieces may exert each its desired degree of pressure upon the bolt F⁷.

The part B²⁰ and the base F may be 25 graduated as shown to indicate the angular inclination of the workholder on the base F, and adjustable stops may be provided to limit this motion of the member B on the base F, for example, to positions in 30 which the work-holder axis is respectively parallel to, and at right-angles to, the underside of the base F. Such an adjustable stop or stops may be formed by one or more cylindrical rods B⁴. Each rod B⁴ is parallel 35 with the axis of rotation of the member B and the ends of each rod fit in holes in the member B, so that the middle of each rod appears in and extends across the T slot B³. Integral with the base F, and within the T slot B³, and adapted to engage the stops B⁴ 40 may be one or more projections forming abutments F¹⁴, and the center part of each rod B⁴ which engages a corresponding abutment F¹⁴ is formed eccentrically (as shown 45 in Figs. 2 and 3) so that by turning the rod

B⁴, as by means of the screw-driver slot B⁰ (Fig. 3) in its end, the circumference of the center part of each rod, which part is the effective portion of the stop, can be moved toward and away from the contiguous abutment F¹⁴. Thus the position of rest of the abutment against the stop can receive minute adjustment whereby the position of rotation of the member B on the base F may be finally precisely adjusted. Set-screws B⁵ 75 are used to clamp the rods B⁴ after the latter are adjusted.

The work-holder A may be in the form shown, i. e. a face-plate having radial T slots or other equivalent means of securing 80 the work thereto, and it may have therein a central hole A¹⁵ in which a plug may be placed for centering the work upon, or through which a bolt may be passed for securing work to the work-holder. Or the 85 work-holder may have the form of a projecting spindle having cylindrical or conical surfaces, or other convenient means such as are well-known, for centering and securing the work, but any such device is herein referred to as a work-holder. Such a work-holder is conveniently provided with a scale of divisions such as A¹⁶ (Figs. 2 and 3) around its periphery, and a "reader" B⁶ (Fig. 1) against which such graduations 90 may be read.

The journal A¹ of the work-holder A is retained against withdrawal from its bearing in B, and adjusted to be free of end-shake by means of a nut A¹⁷ (Fig. 3) threaded on to a projecting end of the journal A¹. To insure that the nut A¹⁷ shall be secure in its position thereon it can be slit radially 100 in one place, and the screw be made a tight fit so that the nut will be held in place by its elastic pressure on the screw.

In order to provide means for determining, apart from the scale of graduations A¹⁶, the operative position or positions of rotation of the work-holder A about its 110 axis, its central hub or journal A¹ has a concentric extension A¹⁸ (Fig. 3) on whose cylindrical exterior may be fitted interchangeably so as to abut against the face of the nut A¹⁷ or an equivalent shoulder any 115 number of catch disks or index plates C (Figs. 4 and 5) having suitable holes, or preferably notches for example C¹ in their peripheries, and adapted to engage a spring-actuated pawl D (Figs. 1 and 3) pivoted 120 on a post B⁷ fixed on the member B. The purpose of the pawl D is to constitute a device against the tip of which the notches of the index plates C may be abutted to give the work-holder A a definite angular position in relation to the bearing in which its journal A¹ is supported.

The index plates C are centered by fitting them closely on the hub A¹⁸, and an index plate can be held adjustably thereon 130

or secured against rotation by means of a separate collar E rotatable and clampable on the hub A¹⁸ by a screw E¹ which closes a slit E² through one side of the collar. The 5 index plate C has in it two holes C² C³ which engage the conical ends of pins E³ and E⁴ projecting from one face of the collar E. The holes and pins are at one common radial distance from the center of the index 10 plate and the holes are preferably placed as shown in Fig. 4 on a straight line through the center of the plate, *i. e.* 180° apart. The pins are, however, so arranged that when partially entered they engage the holes at one common side which is toward the slit E² of the collar E, as shown in Fig. 4, and effectually hold the index plate C against all rotation in spite of normal imperfection in the size or position of the pins or holes 15 C² C³.

20 If, in the entry of one conical pin into its hole, the coned end of the other is not in contact with the wall of the corresponding hole, the pin that has first found a bearing in its hole will, upon the collar being moved toward the index plate, slightly shift the index plate around on the hub until the other hole comes into contact with the other pin, and when the screw E¹ is then tightened to 25 secure the collar it tends to move the pins E³ E⁴, more closely into contact with their respective sides of the holes. Thus the index plate is held finally by a "three-point bearing" of which one point is at the side of the hub remote from the slit in the collar and the other two are at that side of the coned ends of the pins E³ E⁴ which is remote from the first point.

30 The arrangement permits of securing the index plate on the hub A¹⁸ either way around, *i. e.* with either face outward, so that it operates either right or left-handedly.

35 The pawl D may be placed on the post B⁷ either way around so as to suit either the right or left-handed position of the index plate C, and in either such position is held against withdrawal from the post B⁷, and normally urged to engage the index plate, by means of a spring D¹ (Fig. 1) which as 40 shown is held by the screw D³ in the bottom of an open groove machined in one side of the tail end D² of the pawl, the free end of the spring, which is forced or sprung outward from the said groove against its own 45 resistance, engaging in one or other of two transverse open slots or flats B⁸ and B⁹ symmetrically formed transversely in opposite sides of the post B⁷. The spring is so disposed as to engage either of the flats B⁸ or 50 B⁹ at an angle and at that end of the flat which is more remote from the screw D³ than is the opposite end, and the free end of the spring is pressed against that end of the flat by the tension of the spring, for the 55 free end aforesaid is made to react always

toward the post. When the free end of the spring is acting on what is the left hand end in Fig. 1 of the flat B⁹ the reaction at D² of the other end of the spring can bring about a relative motion between the two ends of 70 the spring which is in such a direction as to urge the pawl D around the post negatively, or in a counter clockwise direction; and as at such time the pawl D is in the dotted line position its claw will be pressed toward the 75 index plate.

With the pawl reversed on the post B⁷, which may be accomplished by slipping it off the end of the post and turning it over so that it assumes the position indicated in 80 dot and dash or chain lines, Fig. 1, the spring will act at an angle and on what is the left hand end in Fig. 1 of the upper slot B⁸ and the pawl D will consequently be urged around the post by the spring position 85 toward the index plate.

By turning or rotating the pawl partially around the post until the free end of the spring D¹ bears on the cylindric portion of the periphery of said post the tendency of 90 the spring to turn the pawl is neutralized because for the spring to be effective to perform any work, *e. g.* to turn the pawl, there must be a relative displacement of opposite ends of the spring one in relation to the 95 other, and this is not possible so long as the spring rests on the cylindric part around the axis of which alone the pawl is movable. When the spring is thus resting on the cylindric part of the post the claw of the pawl 100 D is clear of the teeth on the index plate C and will be kept so until the spring is once more made to rest on one or other of the flats B⁸ B⁹.

105 It will be seen that the spring D¹ is so placed as to draw the pawl against that side of the post B⁷ to which the pawl is urged by engagement with the index plate, so that in this way back-lash between the pawl and the post has no effect on the accuracy of 110 dividing.

115 Two edges F¹⁹ and F²⁰ (Fig. 1) of the base F are machined square to one another in plan, the latter being parallel to the axis of the part-cylinder B²⁰, in order to facilitate setting the appliance squarely on any machine to which the apparatus may be held by dogs bearing upon the flanges of the base.

What I claim as my invention and desire to secure by Letters Patent is:—

120 1. A dividing head comprising a rotary work holder having a cylindrical journal connected thereto, a support forming a receiver for the journal and arranged to form a bearing therefor, a portion of said support 125 forming a seat for the journal to accurately position the axis of the journal during the rotation thereof, said support also having a flexible segment arranged to pass around a portion of the journal, and means for se- 130

curing said flexible segment in position to clamp the work holder and force it to its seat, substantially as described.

2. A dividing head comprising a rotary work holder having a cylindrical journal connected thereto, a support forming a receiver for the journal and arranged to form a bearing therefor, said support having two separated bearing surfaces forming seats for the journal to accurately position the axis of the journal during the rotation thereof, together with a flexible segment connected at one end to the support and passing around a portion of the journal, and means for securing said flexible segment in position to clamp the work holder, substantially as described.

3. A dividing head comprising a rotary work holder having a cylindrical journal connected thereto, a support forming a receiver for the journal and arranged to form a bearing therefor, a portion of said support forming a seat for the journal to accurately position the axis of the journal during the rotation thereof, said support also having a flexible segment arranged to pass around a portion of the journal, means for securing said flexible segment in position to clamp the work holder, a pawl support connected to the work holder support, and a pawl pivoted thereto in operative engagement with the work holder, substantially as described.

4. A dividing head comprising a rotary work holder having a cylindrical journal connected thereto, a support forming a receiver for the journal and arranged to form a bearing therefor, said support having two separated bearing surfaces forming seats for the journal to accurately position the axis of the journal during the rotation thereof, together with a flexible segment connected at one end to the support and passing around a portion of the journal, means for securing said flexible segment in position to clamp the work holder, a pawl support connected to the work holder support, and a pawl pivoted thereto in operative engagement with the work holder, substantially as described.

5. The combination of a dividing head work holder and a removable annular index plate on the work holder, of a removable clamp-collar on the work holder, conical ended pins connecting the index plate and the clamp collar arranged to position the index plate with relation to the clamp-collar and force the index plate against a bearing on the work holder, substantially as described.

6. A dividing head having a rotary work holder, an index plate thereon, a fixed cylindrical post having an open slot in its side, a pawl rotatably mounted on the post and adapted to engage the index plate, and a

spring on the pawl adapted to engage one end of the slot to urge the pawl about an axis on the post and to engage the sides of the slot to position the pawl longitudinally on the post, substantially as described.

7. A dividing head having a rotary work holder, an index plate thereon, a fixed cylindrical post having an open slot in its side, a pawl rotatably mounted on the post and adapted to engage the index plate, and a spring on the pawl adapted to engage one end of the slot to urge the pawl about an axis on the post and to engage the sides of the slot to position the pawl longitudinally on the post, the end of the slot having a cylindrical surface concentric with the post, arranged to be engaged by the spring when the pawl is idle, substantially as described.

8. A dividing head comprising a rotary work holder and an index plate thereon, a fixed cylindrical post having an open transverse slot in its side, a pawl rotatably mounted on the post and adapted to engage the index plate, and a spring on the pawl adapted to engage one surface in the slot to urge the pawl about the axis thereof, said spring also being arranged to engage the sides of the slot to position the pawl longitudinally on the post, said spring being so placed upon the pawl as to draw the pawl against that side of the post against which the pawl is urged by the action of the teeth of the index plate, substantially as described.

9. A dividing head comprising a rotary work holder and an index plate thereon, a fixed cylindrical post having an open transverse slot in its side, a pawl rotatably mounted on the post and adapted to engage the index plate, and a spring on the pawl adapted to engage one surface in the slot to urge the pawl about the axis thereof, said spring also being arranged to engage the sides of the slot to position the pawl longitudinally on the post, the end of the slot having a cylindrical surface concentric with the post which is engaged by the spring when the pawl is idle, said spring being so placed upon the pawl as to draw the pawl against that side of the post against which the pawl is urged by the action of the teeth of the index plate, substantially as described.

10. A dividing head comprising a rotary work holder and an index plate thereon, a fixed cylindrical post having two transverse slots in its side, a reversible pawl on said post adapted to engage the index plate, and a spring on the pawl adapted to engage one end of the wall of one slot, to rotate the pawl about the axis thereof toward the index plate, the spring also being arranged to engage both side walls of said slot to retain the pawl in position, the other slot being also adapted to be engaged by the spring when the pawl is reversed, the spring being adapted to urge the pawl in the reverse direction.

when in this position, substantially as described.

11. In a dividing-head the combination of a supporting member, a rotary work-holder journaled therein, a base having a part cylindrical concave surface wherein, a corresponding part cylindrical surface on the supporting member is adjustably seated a flange on the supporting member co-axial 10 with the axis about which said member turns in the base, a clamping bolt which slides endwise in the case and engages the aforesaid flange to clamp the same in the various positions to which it moves relatively to the bolt, and two screw-adjusted thrust rods in sockets in the base and engaged with the shank of the bolt at different places therein, substantially as described.

12. In a dividing head the combination of 20 a rotary work holder, a supporting member therefor having a part cylindrical surface, a base having a counterpart part-cylindrical surface and adapted to carry the supporting member adjustably, a tongue and 25 groove connection between the supporting member and base and means to limit such adjustable movement comprising an adjustable stop within the groove adapted to engage an abutment on the tongue and constituted by a cylindrical rod set in and projecting from a hole in the groove, and means for rotating, and means for clamping it in 30 said hole, the portion of the stop which lies within the groove being eccentric for the 35 purpose described.

13. In a dividing head the combination with a rotary work holder, a cylindric journal fixed upon the holder, a support having a receiver for the journal, the said holder and 40 journal being adjustable radially as a unit relatively to their support, which receiver as to one part thereof is a rigid concavo-cylindric seat to seat the journal accurately and thereby determine with accuracy the 45 position that the axis of the journal shall occupy during the rotation of the journal in said part and as to another part is a flexible segment which is fixed at one end to said receiver and bears on the side of the journal 50 that is out of the rigid seat, the said flexible segment serving to press the journal radially into the seat of the receiver.

14. In a dividing head the combination with a rotary work holder, a cylindric journal 55 fixed upon the holder, a support having a receiver for the journal, the said holder and journal being adjustable radially as a unit relatively to their support, which receiver as to one part thereof is constructed 60 with a rigid concavo-cylindric seat consisting of two separated bearing projections to seat the journal accurately and thereby determine with accuracy the position that the axis of the journal shall occupy during the 65 rotation of the journal in said part and as to

another part is a flexible segment which is fixed by one end to said receiver and bears on the side of the journal that is out of the rigid seat, the said flexible segment serving to press upon that side of the journal which is remote from the two separated bearing surfaces aforesaid so as to press the journal radially into the seat of the receiver. 70

15. In a dividing head the combination with a rotary work holder, a cylindric journal fixed upon a holder, a support having a receiver for the journal, the said holder and journal being adjustable radially as a unit 75 relatively to their support, which receiver is a rigid concavo-cylindric seat as to one part thereof to seat the journal accurately and thereby determine with accuracy the position that the axis of the journal shall occupy during the rotation of the journal in said part and is as to another part as a flexible segment which is fixed at one end to the receiver and bears on the side of the journal that is out of the rigid seat and serves to press the journal radially into the seat of the receiver, a pawl in operative engagement with the 80 work holder, and a pawl support fixed on the aforesaid receiver. 85

16. In a dividing head the combination with a rotary work holder, a cylindric journal fixed upon the holder, a support having a receiver for the holder, the said holder and journal being adjustable radially as a unit 90 relatively to their support, which receiver as to one part thereof is a rigid concavo-cylindric seat consisting of two separated bearing projections to seat the journal accurately and thereby determine with accuracy the position that the axis of the journal shall occupy during the rotation of the journal in said part and as to another part is a 95 flexible segment with one end fixed to said receiver, the said flexible segment serving to press upon that side of the journal which is remote from the two separated bearing projections aforesaid so as to press the journal radially into the seat of the receiver, a pawl in operative engagement with the 100 work holder, and a pawl support fixed on the aforesaid receiver. 105

17. In a dividing head the combination with the work holder of a removable annular index plate on the work holder, a removable clamp collar on the work holder, wedge devices comprising two cone ended pins and constituting an operative connection between 110 the index plate and clamp collar whereby the index plate is caused to take a three point shakeless bearing whereof the three points are respectively on one side of the cone of each pin and on the work holder at one side 115 of the axis of the latter. 120

18. In a dividing head comprising a rotary work holder and an index plate thereon, the combination of a fixed cylindrical post having an open transverse slot in 125 130

its side, a pawl rotatable on the post and adapted to engage the index plate, and a spring on the pawl adapted to engage one end of the slot so as to urge the pawl rotatably on the post and to engage the sides of the slot so as to position the pawl longitudinally on the post.

19. In a dividing head, comprising a rotary work holder and an index plate thereon, the combination of a fixed cylindrical post having an open transverse slot in its side, a pawl rotatable on the post and adapted to engage the index plate, and a spring on the pawl adapted to engage one end of the slot so as to urge the pawl rotationally on the post and to engage the sides of the slot so as to position the pawl longitudinally on the post, the said post having at the end of the slot a cylindrical surface concentric with the post, whereon the spring may be brought to bear when the pawl is to be idle.

20. In a dividing head comprising a rotary work holder and an index plate thereon, the combination of a fixed cylindrical post having an open transverse slot in its side, a pawl rotatable on the post and adapted to engage the index plate, and a spring on the pawl adapted to engage one end of the slot so as to urge the pawl rotationally on the post and to engage the sides of the slot so as to position the pawl longi-

tudinally on the post, and the said spring being so placed upon the pawl as to draw the pawl against that side of the post to 35 which the pawl is also urged by the action upon it of the teeth of the index plate.

21. In a dividing head comprising a rotary work holder and an index plate thereon, the combination of a fixed cylindrical post having an open transverse slot in its side, a pawl rotatable on the post and adapted to engage the index plate, and a spring on the pawl adapted to engage one end of the slot so as to urge the pawl rotationally on the post and to engage the sides of the slot so as to position the pawl longitudinally on the post, the said post having at the end of the slot a cylindrical surface concentric with the post, whereon the spring 50 may be brought to bear when the pawl is to be idle, and the said spring being so placed upon the pawl as to draw the pawl against that side of the post to which the pawl is also urged by the action upon it of the 55 teeth of the index plate.

In testimony whereof I have signed my name to this specification in the presence of two subscribing witnesses.

WILLIAM TAYLOR.
